Primary Examiner — Angela J Lee*Assistant Examiner* — Shawn T Gingrich(74) *Attorney, Agent, or Firm* — Cermak Nakajima & McGowan LLP; Tomoko Nakajima(57) **CLAIM**

The ornamental design for an electrical connector, as shown and described.

DESCRIPTION

FIG. 1 is a front elevational view of an electrical connector showing my new design;

FIG. 2 is a top plan view thereof;

FIG. 3 is a right side elevational view thereof;

FIG. 4 is a left side elevational view thereof;

FIG. 5 is a rear elevational view thereof; and

FIG. 6 is a bottom plan view thereof.

FIG. 7 is a front and top perspective view thereof;

FIG. 8 is a rear and top perspective view thereof;

FIG. 9 is a front and bottom perspective view thereof; and

FIG. 10 is a rear and bottom perspective view thereof.

The broken lines in the drawings illustrate portions of the electrical connector that form no part of the claimed design.

1 Claim, 10 Drawing Sheets(56)
